COLLAPSIBLE JACK

Alton M. Olson, Seattle, Wash.

Application September 25, 1952, Serial No. 311,378

8 Claims. (Cl. 254—1)

1

This invention relates to new and useful improvements in vehicle jacks and the primary object of the present invention is to provide a collapsible vehicle jack that is quickly and readily folded into a small and compact structure for storing, shipping or carrying.

Another important object of the present invention is to provide a collapsible jack including a telescoped base composed of two channel sections that rotatably support jack screw operating rods which are readily coupled together when the sections are extended, whereby a jack screw operatively connected to one of the rods may be rotated from a point remote therefrom.

Another object of the present invention is to provide a collapsible jack of the aforementioned character involving a collapsible handle structure that may be folded over the sections when the latter are disposed in juxtaposition one within the other.

A further object of the present invention is to provide a vehicle jack including a supporting hollow post, a screw actuated tube slidably received in the post and having longitudinally spaced lugs that project laterally from a slot in the post to selectively engage a lifting element slidable on the post, whereby initial longitudinal adjustment of the lifting element relative to the post and tube may be accomplished in order to reduce the time required for moving the lift element against a vehicle part and further providing for variable adjustments of the lift element.

A still further aim of the present invention is to provide a vehicle jack of the aforementioned character that is extremely simple and practical in construction, strong and reliable in use, small and compact in structure, inexpensive to manufacture and maintain, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the present invention and showing the auxiliary channel section disposed in a vertically inclined position;

Figure 2 is an enlarged longitudinal vertical sectional view of Figure 1 but showing the auxiliary channel coaxial with the base channel section;

Figure 3 is an enlarged transverse vertical sectional view taken substantially on the plane of section line 3—3 of Figure 2;

2

Figure 4 is a plan view of Figure 2 in reduced scale and showing the parts of the jack disposed in their carrying position;

Figure 5 is a longitudinal vertical sectional view taken substantially on the plane of section line 5—5 of Figure 4;

Figure 6 is an enlarged transverse vertical sectional view taken substantially on the plane of section line 6—6 of Figure 5;

Figure 7 is an enlarged fragmentary view of Figure 2 with parts broken away and shown in section;

Figure 8 is a horizontal sectional view taken substantially on the plane of section line 8—8 of Figure 7;

Figure 9 is an enlarged fragmentary view of Figure 2 and with parts of the collapsible handle structure broken away for the convenience of explanation;

Figure 10 is an enlarged fragmentary view of Figure 4 the lift element being removed from its carrying position;

Figure 11 is an enlarged detail view of Figure 2 showing the auxiliary channel section raised to an inclined position; and

Figure 12 is a perspective view of the lift element.

Referring now to the drawings in detail, wherein for the purpose of illustration, there is disclosed a preferred embodiment of the present invention, the numeral 10 represents an elongated base channel section having an enlarged forward end 12 that is suitably fixed upon a combined traction plate and skid 14. The plate and skid 14 projects laterally from both sides of the section 10 and its forward end is bent upwardly to form a flange 16 to guide the section 10 as it is slid under a vehicle or the like.

A pair of spaced parallel substantially L-shaped arms 18 are pivoted, as at 20, to the inner faces of the flanges of the section 10 at its forward end for movement into and out of the section 10. The arms 18 are connected by a curved strap 22 that is removably secured about a hollow post 24 by a fastener 26.

The post 24 slidably receives an internally threaded tube 28 having longitudinally spaced teeth or lugs 30 on its outer surface that are slidably received in a longitudinal slot 32 in the post 24. A jack screw 34 is threaded in tube 28 and includes a peripheral groove 36 that receives the inner end of fastener 26 to hold the screw 34 against sliding movement in the tube. The lower end of the screw supports a beveled gear 38 for a purpose presently to be described.

The bifurcated and angulated shank portion

40 of a lift element 42 is slidably received on the post 24. The furcations of portion 40 are connected by a curved part 44 that extends behind the post 24. The lower edge of part 44 is provided with a notch 46 for selectively receiving the lugs 30, whereby the lift element may be adjusted longitudinally of the post and the tube.

The plate and skid 14 fixedly support a vertical socket 48 in which a stub shaft 50 is removably held by a screw 52. The upper end of stub shaft 50 enters a recess in the undersurface of the gear 38 to aid in supporting the gear.

The inturned ends of a U-shaped wire retainer member 54 are pivotally positioned in ears 56 extending upwardly from plate and skid 14. The member 54 extends about the socket 48 and may be raised to the position shown in Figure 5 to engage over the lift member 42 when the latter is removed from the post in order to hold the lift element against the plate and skid 14.

An auxiliary or rear channel section 58 is slidably received in the section 10 and the sections 10 and 58 constitute a telescoped base. The spaced flanges of section 58, at their forward ends, are provided with rounded extensions 60 whose upper edges project upwardly from the flanges to form stops 62 for engaging rollers 64 on a transverse pin 66 extending through the flanges at the rear end of section 10 over section 58, to limit outward sliding movement of section 58 relative to section 10 and to hold the forward end of section 58 relative to the rear end of section 10 as the section 58 is raised on extensions 60 to a vertically inclined position (Figures 1 and 11).

Pin 66 extends through channels 68 formed with the edges of a split bearing sleeve 70 as shown in Figure 3. The sleeve 70 rotatably supports the rear portion of a forward rod 72 whose forward end extends through a forward bearing 74 on the forward end of the section 10 and supports a beveled gear 76 that meshes with gear 38 (Figure 7).

The reinforced rear end 78 of section 58 slidably and rotatably supports a rear rod 80 having a multisided forward end 82 that will enter the socket portion 84 of a universal coupling 86 attached to the rear end of rod 72. A shoulder 88 on the rod 80 forms an abutment for a coil spring 90 that surrounds the rod 80 and which is biased between the end 78 and the shoulder 88 to yieldingly urge the rod 80 forwardly and the end 82 in socket portion 84.

The rear end of rod 80 is provided with a lateral extension 92 that is pivotally attached to one end of a shank 94 having a shoulder 96. A locking sleeve 98 is slidably received on the shank 94 and is urged over the extension 92 by a coil spring 100 that extends about the shank and which is biased between the shoulder 96 and the sleeve 98.

The end of shank 94 remote from the rod 80 is provided with a lateral extension 102 that is pivoted to a short rod 104 having an enlarged free end 106. A locking sleeve 108 is slidably received over the short rod 104 and is formed with an internal rib 110. A coil spring 112 about rod 104 is biased between the rib 110 and the end 106 to urge the sleeve 108 over the extension 102 as well as the short rod 104.

In practical use of the present invention the various parts of the jack will be disposed as shown best in Figures 4 and 5 for carrying of the jack or storage thereof. To use the jack, the retainer 54 is swung downwardly and the lift element removed from the section 10 and placed

over the post 24 until the notch 46 receives a selected tooth 30. Then the element will pivot against the post to be retained therein.

Post 24 is pivoted to a position perpendicular to the section 10 and gear 38 meshes with gear 16 and is supported on the stub shaft 50. Section 58 is then pulled rearwardly from the section 10 and rod 80 is pulled rearwardly relative to section 58 so that end 82 may enter socket portion 84.

Shank 94 is raised so that sleeve 98 will slide over extension 92 and rod 104 is raised so that sleeve 108 will slide over extension 102. Section 58 may be retained in a vertically inclined position, as shown in Figures 1 and 11, with the handle structure 92-112 rotated to raise the tube 28 and the lift element 42 attached thereto.

Having described the invention, what is claimed as new is:

20. 1. A collapsible axle jack comprising an elongated base channel, a jack cylinder pivoted at one end to one of the base channels and swingable into and out of the base channel, an internally threaded tube slidably received in the cylinder, a screw receivably engaged in the tube and rotatably supported by the cylinder, a lift arm attached to the tube and movable therewith, a first operating rod section rotatably supported in the base channel and having one end operatively connected to the screw for rotating the screw, an auxiliary channel slidably received in the base channel and extendable from the other end of the base channel, a second rod section rotatably supported by the auxiliary channel and engageable with the first rod section to permit rotation of the rod sections as a unit, and a hand grip attached to the second rod section, said tube having a plurality of longitudinally spaced teeth thereon, said cylinder having a longitudinal slot 35 slidably receiving the teeth, said arm having an opening receiving the cylinder and a notch accommodating a selected one of the teeth.
2. A collapsible axle jack comprising a telescoped base member composed of two channel shaped sections, a rod rotatably supported by each section, said rods adapted to be disposed one above the other when the sections are disposed in juxtaposition, means releasably coupling the rods together whereby the same may be 40 rotated as a unit when the sections are extended from each other, a hollow post pivoted to one of the sections and movable into and out of said one of the sections, and a lifting member slidably and adjustably carried by the post and operatively connected to the rod supported by the said one of the sections.
3. A collapsible axle jack comprising an elongated base channel, a jack cylinder pivoted at one end to one of the base channels and swingable into and out of the base channel, an internally threaded tube slidably received in the cylinder, a screw receivably engaged in the tube and rotatably supported by the cylinder, a lift arm attached to the tube and movable therewith, a first operating rod section rotatably supported in the base channel and having one end operatively connected to the screw for rotating the screw, an auxiliary channel slidably received in the base channel and extendable from the other end of the base channel, a second rod section rotatably supported by the auxiliary channel and engageable with the first rod section to permit rotation of the rod sections as a unit, and a hand grip attached to the second rod section, said hand grip comprising an elongated shank having a lat-

erally projecting end, a rod element pivoted to said laterally projecting end, a sleeve slidable over the rod element and the laterally projecting end, and a spring retaining the sleeve over the laterally projecting end and the rod element and thereby retaining the rod element and the laterally projecting end coaxial.

4. A collapsible axle jack comprising a telescoped base member composed of two channel shaped sections, a rod rotatably supported by each section, said rods adapted to be disposed one above the other when the sections are disposed in juxtaposition, means releasably coupling the rods together whereby the same may be rotated as a unit when the sections are extended from each other, a hollow post pivoted to one of the sections and movable into and out of said one of the sections, a lifting member slidably and adjustably carried by the post and operatively connected to the rod in said one of said sections, and a collapsible handle structure attached to the rod in the other section and movable into said other section.

5. A collapsible jack comprising a base composed of first and second telescoped channel sections each having an inner end and an outer end, a first rod rotatably supported in the first section, a second rod slidably and rotatably supported by the second section and adapted to underlie the first rod when the first section is disposed within the second section, a hollow post pivoted to the outer end of the first section and movable into and out of the first section, a tube slidably received in the post, a lift element engaged with the tube and slidable with the tube, means operatively connecting the tube to the first rod whereby the tube may be moved longitudinally through the post, a universal coupling element attached to the inner end of the first rod and including a socket portion, said second rod having a multisided end receivable in the socket portion when the sections are extended, and a collapsible handle structure attached to the inner end of the second rod and movable into and out of the second section.

6. A collapsible jack comprising a base composed of first and second telescoped channel sections each having an inner end and an outer end, a first rod rotatably supported in the first section, a second rod slidably and rotatably supported by the second section and adapted to underlie the first rod when the first section is disposed within the second section, a hollow post pivoted to the outer end of the first section and movable into and out of the first section, a tube slidably received in the post, a lift element engaged with the tube and slidable with the tube, means operatively connecting the tube to the first rod whereby the tube may be moved longitudinally through the post, a universal coupling element attached to the inner end of the first rod and including a socket portion, said second rod having a multisided end receivable in the socket portion when the sections are extended, said second rod having a lateral extension at its inner end, an elongated shank pivoted at one end to the extension, a spring urged sleeve slidable on the shank and urged over the extension to lock the shank against pivotal movement, the other end of said shank having a laterally pro-

jecting portion, a short rod pivoted to the last named portion, and a second spring urged sleeve slidable on the short rod and covering the last named portion to prevent pivotal movement of the short rod until the second sleeve is retracted.

7. A collapsible jack comprising a base composed of first and second telescoped channel sections each having an inner end and an outer end, a first rod rotatably supported in the first section, a second rod slidably and rotatably supported by the second section and adapted to underlie the first rod when the first section is disposed within the second section, a hollow post pivoted to the outer end of the first section and movable into and out of the first section, a tube slidably received in the post, a lift element engaged with the tube and slidable with the tube, means operatively connecting the tube to the first rod whereby the tube may be moved longitudinally through the post, means releasably coupling the rods together when the sections are extended to permit rotation of the rods as a unit, and a collapsible handle structure attached to the second rod and movable into and out of the second section, said tube having a series of longitudinally spaced teeth, said post having a longitudinal slot slidably receiving the teeth, said lift element having an opening accommodating the post and permitting sliding movement of the lift element on the post, and said lift element also having a slot for engaging a selected one of the teeth.

8. A collapsible jack comprising a base composed of first and second telescoped channel sections each having an inner end and an outer end, a first rod rotatably supported in the first section, a second rod slidably and rotatably supported by the second section and adapted to underlie the first rod when the first section is disposed within the second section, a hollow post pivoted to the outer end of the first section and movable into and out of the first section, a tube slidably received in the post, a lift element engaged with the tube and slidable with the tube, means operatively connecting the tube to the first rod whereby the tube may be moved longitudinally through the post, means releasably coupling the rods together when the sections are extended to permit rotation of the rods as a unit, and a collapsible handle structure attached to the second rod and movable into and out of the second section, and a transverse pin carried by the inner end of the first section, and stop lugs on the outer end of the second section engageable with the pin as the second section is moved outwardly from the inner end of the first section, to limit sliding movement of the sections away from each other.

ALTON M. OLSON.
